HARRY ALMET JOHNSON AND VICTOR JERHARD PEARSON, OF PIPER CITY, ILLINOIS.

TONGUE-SUPPORTER.

1,142,578.

Specification of Letters Patent.

Patented June 8, 1915.

Application filed February 2, 1915. Serial No. 5,663.

To all whom it may concern:

Be it known that we, HARRY ALMET JOHNSON, a citizen of the United States, and VICTOR JERHARD PEARSON, a citizen of Sweden, 5 and both residents of Piper City, in the county of Ford and State of Illinois, have invented a new and useful Improvement in Tongue-Supporters, of which the following is a specification.

10 Our invention is an improvement in tongue supporters, and has for its object to provide a device of the character specified, adapted for supporting wagon tongues in horizontal position during use, to relieve the 15 necks of the draft animals from the weight of the tongue, and wherein the mechanism is so arranged that the tongue may be quickly released from the supporter or connected therewith to permit the free end of the 20 tongue to rest upon the ground when the wagon is not in use, thus relieving the supporter of the weight of the tongue when the wagon is idle.

In the drawings: Figure 1 is a side view 25 of part of a wagon provided with the improved supporter, and Figs. 2, 3 and 4 are sections on the lines 2—2, 3—3 and 4—4, respectively, of Fig. 1, each looking in the direction of the arrows adjacent to the line.

30 As is known, with the ordinary wagon tongue the horses carry the weight on their collars, and such weight very frequently causes the tops of the necks of the horses to become sore. The necks of the draft animals are also subjected to continual shock 35 and jar when the wagon is in motion.

The present embodiment of the invention is shown in connection with the tongue 1 of a wagon, the tongue having the usual 40 doubletrees 2, connected to the tongue by the bolt and nut 3, the said bolt passing downwardly through the doubletree and the tongue and being engaged by the nut below the tongue. The tongue is connected to 45 the front axle 4 by means of a frame consisting of parallel longitudinally extending bars or hounds 5, connected at their rear ends by upper and lower cross plates 6, the said plates being above and below the reach 50 bar 7 of the wagon.

The axle 4, the bolster 8 and the reach bar 7 are pivoted to each other by the king bolt 9, the said bolt passing downwardly through the bolster, the axle and the reach 55 bar, and being engaged by a nut 10 below the axle. The tongue is connected to the

front ends of the longitudinal bars 5 by means of a bolt 11, the said bolt being passed through the forward ends of the bars 5, through the tongue 1, and through the braces 60 12, arranged on opposite sides of the tongue and engaging the bolts between the rear end of the tongue and the front ends of the bars 5. The bolt 11 is engaged by a nut 13 to hold the parts in place, and it will be evident 65 that the tongue may swing vertically on the bolt. The braces 12 are connected to the tongue in front of the bolt 11 by other bolts or pins 14.

The supporting mechanism comprises a 70 latch in the form of a rod 15, having its forward end flapping laterally and shaped to form a catch 16 and a cam surface 17, adjacent to the catch and in front of the same, the catch being at the rear end of the cam 75 surface. The rear end of the rod 15 is threaded, and is passed through an angular lug 18 on a plate 19, pivoted at its rear end on the king bolt 9, between the reach bar and the upper portion of the axle. Nuts 80 20 are threaded on to the rod on opposite sides of the lug, and it will be evident that by moving the nuts the distance of the catch in front of the axle may be varied.

The catch is adapted to engage a pin 21, 85 which connects the upper inwardly offset ends 22^a of a pair of plates 22, arranged on opposite sides of the tongue and extending above and below the same, the said plates having openings through which the bolt 11 90 passes. The latch at its front end passes between the inwardly offset portion 22^a of the plates 22, and since the latch is below the pin 21 it could not become disengaged 95 from the plate. A coil spring 23 is arranged between the latch and an eye 24 on the bolster and the spring acts normally to lift the latch and to hold the same in engagement with the pin 21. The plates 22 are held at an exact right angle with respect to the tongue, by means of an eye bolt 25, and a flexible member 26. The eye bolt has the eye received between the lower ends of the plates 22, and engaged with a bolt 27 that connects the plates at this point. 100 The bolt extends forwardly through the eye of an eye bolt 28, which is passed vertically through the tongue from below upward, and which holds the reinforcing plate 29 for the bolt 3 at its rear end, the front end of the 110 said plate engaging the bolt 3 above the doubletree.

The flexible member 26 engages at its front end a hook 3^a, formed on the upper end of the bolt 3, and above the head thereof and the rear end of the flexible member 5 engages a pin 30, which connects the upper ends of the inwardly offset portions of the plates 22. A coil spring 26^a is interposed in the length of the flexible member 26, and a flexible member 31 is arranged between 10 the front end of the latch and the bolt 28. The rear end of the flexible member engages an opening in the latch, while the front end is connected to the bolt.

The operation of the improvement is as 15 follows:—When the driver hitches his draft animals he will raise the tongue, and as the tongue is raised the pin 16 will move over the cam surface 17 of the latch, depressing the front end of the latch slightly against 20 the resistance of the spring 23. The pin will pass over the inclined surface and will slip behind the catch. When now the tongue is released, the weight thereof is supported by the latch.

25 The supporting mechanism will release automatically under certain conditions, as for instance, when in driving up an inclined driveway the horses travel beyond the incline with the wagon yet on the incline. In 30 this case the holdbacks on the harness will exert a downward pressure on the tongue and this pressure will extend the spring 26^a sufficiently to cause the flexible connection 35 31 to become taut and depress the latch at its front end thus permitting the tongue to drop and to be supported by the draft animals.

When driving down the driveway, the 40 supporting mechanism will automatically engage as soon as the horses reach the level ground, for the free end of the tongue will be lifted, thus engaging the latch with the pin. Turning of the wagon will not affect the supporting mechanism for the latch can- 45 not move laterally with respect to the plates, and the latch turns with the axle, holding always thus its long axis parallel with the long axis of the tongue.

The supporting mechanism is below the 50 bottom of the bed 32 of the wagon, and is entirely outside of the said bed, so that it does not interfere with the load in the wagon bed. A serious defect in the ordinary form 55 of tongue supporters which are fastened on the wagon bed is that in turning the mechanism does not pull in a direct line with the wagon bed but exerts a sidewise pull on the front end of the wagon box, which tends to strain and racking the wagon.

60 The mechanism requires no changes in the body or bed of the wagon, and the support cannot injure the box or bed, since it is not attached thereto. The device works as well with the bed removed as when the 65 bed is in place, for as before stated, it is

connected with the running gear and not with the bed. Hence the mechanism interferes in no way with the removal or replacement of the bed and the bed is not marred in any way by attaching mechanism. 70 Neither is the tongue or running gear of the wagon weakened in any manner.

We claim:—

1. A wagon tongue supporter, comprising in combination with the running gear and the tongue connected therewith, plates arranged on opposite sides of the tongue at its pivotal connection with the running gear, means in connection with the plates and the tongue for holding the said plates at right 75 angles to the tongue, a latch connected at one end to the king bolt of the wagon and extending forwardly between the plates above the tongue, a pin connecting the plates above the latch, said latch having at its 80 front end a cam surface for engaging the pin to depress the latch when the pin is moved rearwardly with respect to the latch, the latch having a catch at the rear of the cam surface for engaging the pin, a flexible 85 connection between the tongue and the latch for depressing the latch when the tongue is depressed below a certain predetermined point with respect to the running gear, and a yielding connection between the latch and 90 the running gear for normally holding the latch in parallel position.

2. A wagon tongue supporter, comprising in combination with the running gear and the tongue connected therewith, plates arranged on opposite sides of the tongue at its pivotal connection with the running gear, means in connection with the plates and the tongue for holding the said plates at right 95 angles to the tongue, a latch connected at one end to the king bolt of the wagon and extending forwardly between the plates above the tongue, a pin connecting the plates above the latch, said latch having at its front end a cam surface for engaging the pin to de- 100 press the latch when the pin is moved rearwardly with respect to the latch, the latch having a catch at the rear of the cam surface for engaging the pin, and a flexible connection between the tongue and the latch for 105 depressing the latch when the tongue is de- 110 pressed below a certain predetermined point with respect to the running gear.

3. A wagon tongue supporter, comprising in combination with the running gear and the tongue connected therewith, a pair of plates arranged on opposite sides of the tongue at the pivotal connection, means for normally holding the plates at a right angle 115 to the tongue, said means being mounted to yield, a latch connected to the king bolt and extending forwardly between the plates above the tongue, a pin connecting the plates above the latch, said latch having a cam sur- 120 face at its front ends for engaging the pin 125 130

to depress the free end of the latch, and having a catch at the rear of the cam surface for engaging the pin to hold the tongue elevated, a connection between the latch and 5 the tongue for depressing the free end thereof when the free end of the tongue is lowered beyond a predetermined point.

4. A wagon tongue supporter, comprising in combination with the running gear and 10 the tongue connected therewith, a pair of plates arranged on opposite sides of the tongue at the pivotal connection, means for normally holding the plates at a right angle to the tongue, a latch connected to the king 15 bolt and extending forwardly between the plates above the tongue, a pin connecting the plates above the latch, said latch having a cam surface at its front ends for engaging the pin to depress the free end of the latch, 20 and having a catch at the rear of the cam surface for engaging the pin to hold the tongue elevated.

5. A wagon tongue supporter, comprising in combination with the running gear and 25 the tongue pivoted thereto, a resilient latch connected to the running gear of the wagon and turning with the front axle, a pin connected to the tongue for engagement by the

latch to hold the tongue in horizontal position, resilient means for holding the latch in 30 engagement with the pin, a connection between the latch and the tongue for releasing the latch when the free end of the tongue is lowered below a predetermined point, the latch having a cam surface for engagement 35 by the pin when the tongue is lifted to depress the latch and to guide the latch into engagement with the pin.

6. A wagon tongue supporter, comprising in combination with the running gear of a 40 wagon and the tongue pivoted thereto, a latch on the running gear, a catch in connection with the tongue for engagement by the latch, means in connection with the latch and the catch for guiding the catch into 45 engagement with the latch when the free end of the tongue is lifted, and a connection between the tongue and the latch for releasing the latch when the free end of the tongue is depressed below a predetermined 50 point.
